UNITED STATES PATENT OFFICE.

HENRY HAASE, OF PHILADELPHIA, PENNSYLVANIA, ASSIGNOR TO THE
HENSEL, COLLADAY COMPANY, OF PENNSYLVANIA.

DESIGN FOR GARMENT-EDGING.

SPECIFICATION forming part of Design No. 26,189, dated October 13, 1896.

Application filed August 8, 1896. Serial No. 602,201. Term of patent 14 years.

To all whom it may concern:

Be it known that I, HENRY HAASE, a citizen of the United States, residing in the city and county of Philadelphia, State of Pennsylvania, have invented and produced a new and original Design for Garment-Edging, of which the following is a specification, reference being had to the accompanying drawing, forming part thereof.

5 The leading feature of my design for a garment-edging is a body having thereon a spiral border with a tufted or fluffy surface.

10 The figure represents a face view of a piece of garment-edging embodying my design.

A designates a piece of braid or fabric comprising the body of the edging.

B designates a border thereon, the same being of spiral form and presenting a tufted or fluffy appearance.

15 What I claim is—

20 The design for garment-edging substantially as described and shown.

HENRY HAASE.
